Patented Sept. 3, 1974

232,606

COMBINED TOILET-TISSUE HOLDER AND CONTAINER SUPPORT

Philip Boone, 15 Fenwick Road,
Winchester, Mass. 01890

Filed May 4, 1972, Ser. No. 250,479

Term of patent 14 years

Int. Cl. D6—06

U.S. Cl. D6—91

FIG. 1

FIG. 2

FIG. 1 is a front perspective view of a unitary toilet-tissue holder and container mount showing my new design; and

FIG. 2 is a side elevational view thereof.

I claim:

The ornamental design for a combined toilet-tissue holder and container support, as shown.
